UNITED STATES PATENT OFFICE

2,080,945

MOP WRINGER

Thomas Franklin Lee, Atlanta, Ga.

Application October 29, 1935, Serial No. 47,324

1 Claim. (Cl. 15—262)

This invention relates to mop wringers and has for an object to provide a mop wringer which may be folded into compact form when not in use and which may be unfolded and set up over a pail or small tub to conveniently and quickly wring out mops of all sizes.

A further object is to provide a mop wringer including a frame and hinged supporting legs therefor, the frame being equipped with a pair of wringing rolls, one of which is adapted to be moved toward the other roll by a novel foot pedal having the ends slidably mounted in guides disposed on one pair of the supporting legs so that the operator may exert great pressure on the 15 movable roll when wringing out very heavy mops.

A still further object is to provide a device of this character which will be formed of a few strong, simple, and durable parts, which will be inexpensive to manufacture, and which will not 20 easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any 25 of the advantages of the invention.

In the accompanying drawing forming part 30 of this specification,

Figure 1 is a longitudinal sectional view of a 35 mop wringer constructed in accordance with the invention.

Figure 2 is a vertical sectional view taken on the line 2—2 of Figure 1.

Figure 3 is a detail sectional view taken on the line 3—3 of Figure 2.

Referring now to the drawing in which like characters of reference designate similar parts in the various views, the device is shown to comprise a substantially rectangular frame 10 preferably formed of square tubing and the frame is supported at the opposite ends by pairs of legs 11 which may be formed of wood. Each pair of 40 legs is hinged to the side rails 12 of the frame by means of strap hinges 13 so that the legs may be folded flat against the bottom of the frame when the device is not in use and may be unfolded to the vertical position when the device 45 is to be used. The upper ends of the legs overlap the end rails 14 of the frame when the legs are rocked to operative position and are held pressed tightly against the end rails by oblique braces 15.

50 The braces are formed of metal straps pivotal-

ly connected together at the inner ends as shown at 16, and are pivoted at the outer ends to the side rails of the frame and to the associated legs, as shown at 17. One member of each brace is provided on the underneath face with a lip 18 5 which engages the bottom edge of the mating member and holds the brace in extended position until the pivot 16 is manually displaced toward the adjacent hinge 13 to "break" the brace and permit of the associated legs 11 being 10 folded.

A wringing roll 19 is mounted to idle on a shaft 20 which is journaled at the ends in suitable openings in the inner side of the tubular side rails 12. A second wringing roll 21 is fixed 15 on a shaft 22 which extends at the ends through blocks 23 which are slidably fitted in the bores of the tubular side rails 12. Helical springs 24 are secured to eyes 25 carried by the blocks and to eyes 26 carried by the adjacent end rails 14 of 20 the frame and yieldably hold the blocks in position to maintain the wringing roll 21 sufficiently spaced from the wringing roll 19 so that mops of various sizes may be received between the rolls.

For moving the slidably mounted wringing 25 roll 21 toward the wringing roll 19 a pair of chains 27 are secured to eyes 28 carried by the blocks 23 and these chains are trained over guide pulleys 29 which are mounted within the bores of the side rails and thence are trained 30 downwardly through openings 30 in the side rails and connected at the ends to a bar 31 which forms a foot pedal. The ends of the bar are slidably fitted in U-shaped guide bars 32, as best 35 shown in Figure 3, the guide bars preferably being secured to the associated legs 11 by screws 33 passed through the ends of the guide bars and into the legs. An arcuate strap 34 is secured by rivets 35 or similar connectors to the foot pedal 31 and coacts with the latter in forming a pedal of suitable width against which the operator may rest the foot to depress the pedal and through the instrumentality of the chains 27 move the roll 21 toward the roll 19.

The legs are braced near their lower ends by 45 transverse braces 36 which prevent spreading of the legs under severe conditions of service.

A crank handle 37 is formed integral with the shaft 22 of the roll 21 and forms means for manually rotating the latter after the mop is inserted between the rolls and the roll 21 advanced toward the roll 19 by depressing the foot pedal 31. Slots 38 are formed in the side rails 12 of the frame to receive the projecting ends of the 50 55

shaft 22 of the movable roll 21 and to receive the upper end of the crank handle 37.

In operation, the legs 11 are rocked downwardly and the braces 15 are then extended to hold the legs in position to maintain the frame 10 horizontal. A small tub or bucket may be placed underneath the frame to catch the water wrung from the mop. The mop is then inserted between the rolls 19 and 21 whereupon the operator depresses the foot pedal 31 to move the roll 21 toward the roll 19 and compress the mop between the rolls. The operator then turns the crank handle 37 to rotate the roll 21 and feed the mop through the rolls 19 and 21. By virtue of the guides 30 being disposed on the legs 11 the downward pressure of the operator's foot is borne by the legs 11 which are thus more tightly forced against the floor and the operator is thus enabled to exert great pressure upon the movable roll 21 without upsetting the mop wringer.

From the above description it is thought that the construction and operation of the invention will be fully understood without further explanation.

What is claimed is:

A mop wringer comprising a substantially rec-

tangular frame having side and end bars formed of tubing, supporting legs for the frame hinged to and overlapping the end bars of the frame, a stationary wringing roll journaled in the side bars, guide blocks slidably fitted in the tubular side bars of the frame, a wringing roll journaled in said guide blocks, springs connected to one of the end bars of the frame and housed within the bores of the side bars of the frame and connected to the guide blocks for holding the last named wringing roll spaced from the stationary wringing roll, flexible connectors secured to the guide blocks at the opposite ends thereof from the springs, a cross bar connected to said flexible connectors, said cross bar forming a pedal, guides on a pair of the legs slidably receiving the ends of the pedal, depression of the pedal moving the guide blocks to move the associated wringing roll toward the stationary wringing roll against the tension of the springs, and a crank handle connected to one of the wringing rolls for rotating the roll to feed the mop between the wringing rolls when the wringing rolls have been moved by the pedal and the connectors to operative position to squeeze a mop between them.

THOMAS FRANKLIN LEE.
